MULTIPLE COIN METER

Harry Greenwald, Whitestone, N.Y., assignor of one-third each to Louis Wolff and Harry Silberglaib, both of Brooklyn, N.Y.

Filed June 6, 1962, Ser. No. 200,395

8 Claims. (Cl. 194—9)

This invention relates in general to a multiple coin meter, and more specifically to a compact multiple coin meter adapted for accepting coins of different denominations.

An object of this invention is to provide a multiple coin meter having a single coin slot sized for receiving coins of several denominations.

Another object is to provide a multiple coin meter adaptable for receiving coins of several denominations with means for imparting an electrical impulse for totaling the amount of the acceptable coins received thereby.

Another object is to provide a multiple coin meter having a coin rejecting means for each of the coin denominations accepted by the meter to distinguish between acceptable and unacceptable coins accepted by the respective coin rejecting means and in which the coin rejecting means are disposed in side by side relationship to minimize the vertical fall distance of the respective coins therethrough.

Another object is to provide a multiple coin meter with a single electromagnetic means for preventing the acceptance of any coins by the machine controlled by the coin meter when there is no power to the machine.

Another object is to provide a multiple coin meter with a coin separator disposed adjacent the coin slot which is operatively associated with the coin rejecting means for directing like coins of one denomination to one coin rejecting means and for directing like coins of another denomination to another coin rejecting means.

Still another object is to provide a trip switch operatively associated and arranged so that the switch is actuated by a coin each time an acceptable coin passes through its respective coin rejecting means.

Still a further object is to provide one trip switch operatively associated with the meter components whereby the one switch is successively actuated at least twice by the same coin; and which one switch is constructed and arranged so as to prohibit hang up of the coin thereon.

Still a further object is to provide in a multiple coin meter, multiple coin rejecting means with a single clearing lever actuated from the front of the meter for effecting simultaneous clearing each of the coin rejecting means.

The above objects, and other features and advantages of this invention are attained by a multiple coin meter comprising a front plate having formed therein a single slot sized for receiving coins of several denominations, and a coin return opening. Disposed adjacent the coin slot is a coin separator for distinguishing the denomination of the coin inserted into the meter. Positioned on the opposite sides of a bracket connected to the front plate is a coin rejecting means for detecting between acceptable and unacceptable coins of the denomination received thereby, the separator directing like coins of one denomination to the coin rejecting means disposed on one side of the bracket and like coins of another denomination to the other coin rejecting means disposed on the other side of the bracket.

Operatively associated, with each of the coin rejecting means is a coin chute. Each coin chute is arranged to define an acceptable coin channel and an unacceptable coin channel; the latter coin channel of the respective coin chutes returning the unacceptable coins passing through the respective coin rejector to the coin return opening. The acceptable coins detected by the respective coin re-

2

jector means are directed through the acceptable coin channel to the coin box of the machine. A single electromagnetic means is disposed between the respective coin rejecting means. In its deenergized state the electromagnet will cause the coins to fall in the unacceptable coin channel of the respective coin chutes for ultimate return to the coin return box or opening. In its energized state, the electromagnet permits the accepted coins passing through the respective rejector means to drop in the coin accepting channel of the coin chutes.

In accordance with this invention there is associated with each of the acceptable coin channels a trip switch having means in the form of a feeler or trip disposed in the path of the coin so as to be actuated by the acceptable coin passing thereby. One of the trip switches is arranged to be actuated twice by the same larger denomination coin. The arrangement is such that an impulse generated upon the respective actuations of the trip switches is used for totaling the value of the coins accepted. The coin meter of this invention also includes a clearing lever pivotally mounted to the bracket. The clearing lever is operatively associated with the clearing mechanism of the respective coin rejecting means so that actuation of the clearing lever from the front of the meter serves to simultaneously actuate the rejecting mechanisms of the respective coin rejecting means.

A feature resides in the provision that the multiple coin meter of this invention is positive and reliable in operation.

Other features and advantages will become more readily apparent when considered in view of the drawings and description in which:

FIG. 1 is a front view of the multiple coin meter of this invention looking at the front plate of the meter;

FIG. 2 is a rear view of the coin meter;

FIG. 3 is a detail side view of the bracket and clearing lever assembly;

FIG. 4 is a plan view of FIG. 3;

FIG. 5 is a right end view of the bracket assembly of FIG. 4;

FIG. 6 is a side view of the mounting bracket assembly;

FIG. 7 is a right end view of FIG. 7;

FIG. 8 is a plan view of FIG. 6;

FIG. 9 is a side view in detail of a coin chute;

FIG. 10 is a plan view of FIG. 9;

FIG. 11 is a right end view of FIG. 9;

FIG. 12 is a plan view of the separator means for mechanically distinguishing between coin denominations, and

FIG. 13 is an enlarged detail of the switch trip wire.

Referring to the drawings, FIGS. 1 to 13 illustrate the compact multiple coin meter 20 of this invention. The multiple meter 20 is adapted to receive coins of different denominations, as for example, twenty-five cent coins and fifty cent coins. However it will be understood, that while reference will be herein made to coins of these denominations, the meter concept of this invention can be readily adapted for use with coins of any denomination, e.g. five cent coins, ten cent coins, and the like.

Meters of this type are used, for example, on commercial, coin operated, automatic washers, dryers, dry cleaning machines, and the like. In accordance with this invention the compact meter 20 comprises a front plate casting 21 having formed therein a single coin slot opening 22 sized for receiving both twenty-five cent coins and fifty cent coins. The front plate 21 is also provided with a coin return box 23 in which access is had through an opening 24 in the front plate. If desired a swinging door (not shown) may be provided to close the access opening 24 to the coin return box 23. Also the front of the plate is provided with a coin return lever 25 and

a suitable lock means 26 of known construction having a rotating latch 26A for securing the meter front plate to a given coin operated machine, e.g. an automatic washer, drier, and the like (not shown).

Connected to the rear of the front plate in the vicinity of the coin slot 22 is a coin separator 27 for distinguishing between the fifty cent coins and the twenty-five cent coins. The separator 27 comprises a casting having a passageway 27A for receiving the twenty-five cent coins and a passageway 27B for receiving fifty cent coins. Operatively associated with the separator casting is a separating baffle 28 which is constructed to direct the larger fifty cent coins to passageway 27B, and the smaller twenty-five cent coins to passageway 27A. The baffle comprises a bent portion 28A for directing the larger of the two coins to one passageway 27B and having another lower position 28B thereof oppositely bent for directing the smaller of the coins to the other passageway 27A. The arrangement of the separator casting 27 and associated baffle 28 is such that the coins are readily distinguished mechanically regardless of the order in which the coins are inserted into the coin slot.

Connected to the rear of the front plate is a mounting bracket assembly 29. The assembly 29 includes a mounting bracket 30 connected normally to the front plate 21 by means of a laterally bent front mounting flange 30A. The bracket 30 also includes a flange 30B integrally connected and laterally disposed to the same side of the bracket 30 as the front mounting flange 30A. Extending to the other side of the bracket 30 are laterally bent out tabs or ears 30C, 30D, 30E to provide a three point support for coin rejecting mechanism 31 detachably connected thereto as will be hereinafter described. The front and rear flanges 30A, 30B are each provided with notches 32 for detachably supporting therebetween another coin rejecting mechanism 33.

As shown in FIG. 2, the bracket 30 is disposed normal to the front plate 21 immediately below the coin separator 27 and is arranged relative thereto so that one coin passageway 27A is positioned to one side of the bracket 30, and the other coin passageway 27B is positioned to the other side of the bracket 30. The central portion of the bracket 30 is provided with a cut out portion or opening 34 for accommodating an electromagnetic means 35 comprising a coil 35A disposed about a stationary core 35B. Pivotally connected adjacent the core of the electromagnetic means about a fulcrum F is a hinge plate 36. In the deenergized state of the electromagnet 35, i.e. when there is no power to the machine, the plate 36 is normally biased outwardly of the core by a spring 36A as shown in FIG. 6. Connected to the deflecting plate 36 is a pin 36B by which the coins of one denomination are actually deflected when the electromagnet is deenergized. In the energized state of the electromagnet, the hinge plate 36 is attracted to the core so as to render the plate 36 inoperative. Operatively connected to an extension 36C connected to the plate 36 is a deflecting lever 37. As shown, lever 37 is pivoted intermediate the ends thereof about pin 38 to bracket 30. The lever 37 is adapted to project through an opening 30F in the bracket 30 to extend to the other side thereof. Thus when the electromagnet 35 is energized and the plate 36 is attracted to the core, both the pin 36A and the deflecting lever 37 connected to the plate 36 are moved from operative to inoperative position as will be hereinafter described.

Connected to either side of the bracket 30 are coin chute assemblies 40 and 41. Coin chute assembly 40 is adapted to accommodate the twenty-five cent pieces; and coin chute assembly 41 is adapted to accommodate the fifty cent pieces.

As shown in FIGS. 9-11, the fifty cent chute assembly is defined by an inner and outer wall 41A, 41B. The outer wall 41B tapers downwardly and inwardly and is formed with integral inwardly bent bottom wall 41C

which inclines toward the coin reject box 23. The inner wall 41A spaced from the outer wall 41B defines therewith a coin channel 42 for receiving the fifty cent coins unacceptable to the fifty cent coin rejecting means 33. Disposed between the inner and outer wall 41A, 41B adjacent the rear portion of the chute assembly 41 is a partition wall 41D to define with a portion of the inner wall 41A, a channel 43 for receiving the acceptable fifty cent coins. Channel 43 communicates with the coin reservoir of the machine which is not shown.

As shown in FIG. 8, the coin deflecting lever 37 has its end portion 37A overlying the inlet to the acceptable fifty cent coin channel 43 in the deenergized position of electromagnet 35. Therefore, in the deenergized position of the electromagnet 35, it is impossible for a fifty cent coin deposited in the coin slot 22 to be accepted in the acceptable coin channel 43, as channel 43 is blocked by lever 37. The blocking end 37A of the lever 37 is provided with an inclined cam surface 37B for deflecting the fifty cent coins to the reject channel 42 when the electromagnet 35 is deenergized.

The twenty-five cent return coin channel 40 comprises a casting which is connected on the opposite side of the bracket 30. The inlet 40A of this channel is blocked in the deenergized state of the electromagnet 35 by the deflecting pin 36B on plate 36. Disposed adjacent to the return coin channel 40 is the acceptable twenty-five cent channel 45. This channel 45 also communicates with the coin box of a meter which is not shown. As shown, the coin channel 45 is defined by a stamping bent to define a rectangular chute or channel, the sides of which is provided with an elongated opening 43A.

In accordance with this invention, a coin reject means 31, 33 is detachably secured to each side of the bracket 30 between the coin separator 27 and the respective coin chute assemblies 40 and 41. Each of the coin reject means 31, 33 are of standard well known construction, and the specific details thereof do not form any part of this invention. For this reason, a detailed description of these reject mechanisms are not essential for an understanding of the invention. Generally the reject devices 31, 33 are utilized for distinguishing between acceptable and unacceptable coins of each denomination accepted by the coin slot of the meter. For example, the respective reject means 31, 33 are constructed so that they will only accept proper sized coins. Undersized coins, counterfeit coins, washers, slugs and the like are rejected by the respective coin rejectors. In the instant case the unacceptable coins or coin facsimiles are hung up in either of the respective rejecting means 31, 33, and must be cleared by the clearing lever 50. The acceptable coins pass through their respective rejecting mechanism to the coin channels 43 or 45 leading to the coin box (not shown).

As shown in FIG. 2, the twenty-five cent rejecting mechanism 31 is provided with laterally extending pins 31A whereby it is detachably supported on lugs 30C, 30D and 30E. The rejecting means 31 is positively retained in place by a latch 51 which is pivoted to flange 30B for movement between latched and unlatched positions. The fifty cent rejecting mechanism 33 is disposed on the other side of the bracket 30 between flanges 30A and 30B; and it is positively retained therebetween in a similar manner by latch 52. In the assembled position it will be apparent that all coins inserted through coin slot 22 will be directed through one or the other of the reject mechanisms 31 or 33, and be discharged therefrom to the coin chute assembly disposed therebeneath. Depending on whether the coin has been accepted or unacceptable by the respective coin rejecting means, the coin passing therethrough will be directed to either the acceptable coin channel leading to the coin box, or to the return coin channel leading to the coin return of the respective coin chute assemblies.

For clearing the respective coin rejecting means 31, 33, a common clearing lever 50 is pivoted to the bracket 30.

The lever 50 is provided with a pair of oppositely disposed lugs 50A, 50B which are arranged to engage the clearing mechanism of the respective rejecting means 31, 33. The actuator for the lever 50 comprises the coin return lever 25 which is pivoted on the front plate. Connected to the pivot 25A of lever 25 is an arm 25B which engages one end of the clearing lever 50. Thus when the return coin lever 25 is actuated, the clearing lever 50 will be operated to effect actuation of the clearing mechanism of the respective coin rejecting means to release any unacceptable coin hung up therein, in the event an unacceptable coin has been deposited. Upon release of the unacceptable coin, it is directed to either of the appropriate coin return channels 40, 42.

In accordance with this invention means for creating an electrical impulse for totaling the amount of acceptable coins received thereby is provided. The electrical impulses are produced by a trip switch 60, 61 disposed adjacent each of the acceptable coin channels 45, 43, respectively. Each of the switches 60, 61 are arranged so as to be actuated by the coin passing through the respective acceptable coin channel. Because the fifty cent coin is equal to twice the value of the twenty-five cent coin, the switch 61 adjacent the fifty cent acceptable channel 43 is arranged so as to be actuated twice by the same acceptable fifty cent coin. The switch 61 adjacent the twenty-five cent channel 45 is actuated once by the coin passing therethrough. In this manner the number of impulses produced by the coins passing through chambers 43 and 45 are identified by the value of the coins accepted by the respective coin rejectors.

In accordance with this invention the trip switch 60 for the twenty-five cent coins includes a feeler or trip wire 60A which has a laterally bent end portion 60B extending transversely across the width of the acceptable coin channel 45. Therefore each acceptable twenty-five cent piece passing through channel 45 will engage the bent end 60B of feeler 60A. Such engagement will effect displacement of the feeler and actuation of the switch 60.

The trip switch 61 adjacent the acceptable fifty cent coin channel 43 includes a feeler or trip wire 62 which is pivoted to the switch 61 intermediate the ends thereof. Thus the feeler wire 62 has a pair of arms 62A, 62B. One arm has a laterally bent end portion 62C adapted to extend transversely of the acceptable coin slot 43 adjacent the upper rear end of the channel 43. The other arm 62B has a laterally bent portion 62D extending through opening 43A disposed in the lower front portion of the channel 43, diametrically opposite the upper portion 43B of channel 43. The arrangement of feeler or trip wire 62 is such that an acceptable fifty cent coin passing through channel 43 will first trip arm 62A, and then successively trip arm 62B; thus the fifty cent piece will trip the switch 61 twice.

Because a fifty cent coin has a knurled periphery edge, and because a part of its momentum is lost in actuating the trip arm 62A, the lateral bent end portion 62D of the second trip arm 62B is constructed so as to prevent hang up of the coin therein. Hangup is thus avoided by providing a V shape notch 63 (FIG. 13) intermediate the bent end portion 62D. Thus, when the fifty cent coin engages the bent portion 62D of arm 62B, the edge of the coin is received in the V of the notch 63 so that the trip of arm 62B is, in effect, actuated by the sides of the fifty cent coin. In this manner the knurled edge of the fifty cent piece does not engage the bent portion 62D of the trip arm 62B.

If desired, the front plate may be provided with a window 70 in which the total amount required for operating the machine may be displayed. The arrangement is such that the amount sign (not shown) cannot be removed from the front of the meter. A space 71 for displaying the operating instructions is also provided on the front plate.

In operation, the multiple coin meter is adapted to be used in an automatic coin operated machine, as for ex-

ample, a washer, drier, dry cleaning machine, or the like. The meter described is utilized in conjunction with a coin counter which does not form any part of this invention. The impulses or signals produced by the accepted coins tripping switches 60, 61 are sent to the coin counter. Thus when the proper number of coins have been deposited, the counter will initiate the operating cycle of the machine. For example, if the counter has been set to initiate a cycle upon the insertion of, say \$1.75, in 10 coins, any combination of fifty cent and twenty-five cent coins for totaling this amount must be deposited in the coin slot 22 of the meter. For example, if the operator deposits two fifty cent coins and three twenty-five cent coins, the fifty cent coins will be directed by separator 15 27 to the fifty cent coin reject mechanism 31, and the twenty-five cent coins will be directed to the twenty-five cent reject mechanism 31. With the power connected to the machine, and electromagnetic means energized, the respective coins passing through their respective rejecting mechanism are directed to either of the acceptable coin channels 43 or 45, if they be proper and valid coins. In doing so the respective coins will trip either switch 60 or 61. The signal resulting from the tripping of switches 60 or 61 is thus relayed to the coin counter which is 20 25 tied in with the circuits operating the given machine cycle.

While the instant invention has been disclosed with reference to a particular method and a particular embodiment for practicing the same, it is to be appreciated that 30 the invention is not to be taken as limited to all of the details thereof as modifications and variations thereof may be made without departing from the spirit or scope of the invention.

What is claimed is:

35 1. A compact totalizing multiple coin meter comprising a front plate having a single coin slot sized for receiving coins of different denominations; separator means connected to the front plate adjacent said slot for distinguishing the denomination of said coins; a coin rejecting means disposed adjacent to said front plate for each denomination, said separator means directing coins of like denomination to one rejecting means, and like coins of another denomination to another rejecting means, each said rejecting means including means for distinguishing between acceptable and non-acceptable coins of said coin denominations, a trip switch associated with each of said rejecting means, said trip switches each including an actuating trip feeler disposed in position to be actuated by an acceptable coin passing through its respective rejecting means, and one of the switches having a trip feeler having opposed ends, said one switch being arranged to be actuated at least two times by the same coin, the said trip feeler of said one of the switches including means for pivotally connecting said trip feeler of said one switch intermediate its opposed ends, and laterally bent end portions formed at each of said opposed ends, said bent end portions being disposed to extend in the path of a coin whereby the bent end portions are directly and successively actuated by the same coin passing through the associated rejecting means whereby each actuation of said 50 55 60 trip feeler by said coin imparts an impulse upon engagement of said coin with each bent end portion whereby the total of said impulses indicates the denomination of said coin.

2. A compact multiple coin meter for accepting coins 65 of different denominations comprising a front plate having a single coin slot sized for receiving coins of different denominations and a coin return opening, a bracket connected to the rear side of said front plate; said bracket having an opening therein; an electromagnet mounted in 70 said opening, said electromagnet having means for rejecting all coins when said electromagnet is rendered inoperative whereby said coins are returned to the coin return opening, a coin rejecting means mounted on either side of said bracket, the coin rejecting means mounted on one 75 side of said bracket distinguishing between acceptable and

unacceptable coins of one denomination, and the coin rejecting means on the other side for distinguishing between acceptable and unacceptable coins of another denomination; means for clearing said rejecting means simultaneously; and a handle pivotally mounted on said front plate for actuating said clearing means for ejecting any unacceptable coin in either of said coin rejecting means; a coin separator disposed adjacent said slot, said separator directing coins of like denominations to one rejecting means and all like coins of another denomination to the rejecting means on the other side of said bracket, a trip switch including a trip feeler operatively associated with the respective coin rejecting means, each of the trip feelers of the respective trip switches being disposed so as to be actuated by an acceptable coin passing through its respective rejecting means; and one of said trip switches including a trip feeler whereby said feeler is actuated at least twice by the same coin, whereby actuation of trip switches imparts an impulse for totaling the amount of coins deposited.

3. A compact multiple coin meter for accepting coins of different denominations comprising a front plate having a single coin slot sized for receiving coins of different denominations and a coin returning opening, a bracket connected to the rear side of said front plate; said bracket having an opening therein; an electromagnet mounted in said opening, said electromagnet having means for returning the coins to said coin returning opening, "a coin rejecting means mounted on each side of said bracket, the coin rejecting means on one side being operative to distinguish between acceptable and unacceptable coins of any denomination, and the coin rejecting means on the other side of said bracket for distinguishing between acceptable and unacceptable coins of another denomination; means for clearing said rejector simultaneously, said latter means including a clearing lever pivoted to said bracket, said lever including lateral projections adaptable, for engaging the clearing mechanism of said coin rejections, and handle pivotally mounted on said front plate for actuating said clearing lever for ejecting any unacceptable coin in either of said coin rejecting means; a coin separator disposed adjacent said slot, said separator directing coins of like denominations to one rejecting means and all like coins of another denomination to the rejecting means on the other side of said bracket, a trip switch including a trip feeler operatively associated with the respective coin rejecting means, each of said trip switch feelers being disposed so as to be actuated by an acceptable coin passing through its respective rejecting means, and one of said trip switch feelers including means whereby said switch feeler is actuated at least twice by the same coin.

4. A compact multiple coin meter adapted for use in a coin operated machine for accepting coins of different denominations comprising a front plate having a single coin slot sized for receiving coins of different denominations and a coin return opening, a return box disposed adjacent said opening, a mechanical coin separator disposed immediately behind said slot, a bracket connected to said front plate, a coin chute connected to each side of said bracket for receiving coins of like denominations which are directed to said chutes by said separator, means for partitioning each of said coin chutes into an acceptable coin channel and an unacceptable return coin channel, said return coin channel of the respective coin chutes communicating with said coin return box, and an electromagnet connected on said bracket, means associated with said electro-magnet for preventing the passage of any coins from said coin slot to either of said coin accepting channels of said coin chutes when a coin is inserted into said coin slot and said electro-magnet is de-energized, a coin rejector mounted on either side of said bracket between said separator and said coin chutes, said separator directing like coins of one denomination to one coin rejector and like coins of another denomination to an-

other rejector, each of said rejectors being operative to distinguish between acceptable and unacceptable coins of the coin denomination accepted thereby, said rejectors directing its acceptable coins to the acceptable coin channel of its respective coin chute, and directing its unacceptable coins to the unacceptable coin channel of the respective coin chute, a trip switch associated with the acceptable coin channels of each coin chute, said trip switch being actuated by the coin passing through its respective acceptable coin channel whereby said switch actuation generates an impulse for totaling the amount of the acceptable coins accepted by said meter, the switch associated with one of said chutes having means whereby said switch is actuated at least twice by the same coin, said latter means includes a two armed trip feeler pivotally connected to said switch, each arm of said trip feeler having a lateral bent end portion adapted to be contacted by said coin, and one of said laterally bent end portions being provided with an offset portion for engaging the sides of a coin actuating the same for minimizing hang-up of said coin.

5. The invention as defined in claim 4 including means for simultaneously clearing said rejectors; said means including a clearing lever pivotally mounted to said bracket, said lever being adapted to engage the clearing mechanisms of the respective coin rejectors, and a handle pivotally mounted on the front plate for actuating said clearing lever.

6. A compact multiple coin meter for use in a coin operated machine for accepting for example both twenty-five and fifty cent coin pieces comprising a front plate having a single coin slot for receiving each of the respective coin pieces and a coin return opening; a return coin box disposed adjacent said return opening; a mechanical coin separator disposed immediately behind said slot for distinguishing between the respective coin pieces, a bracket connected to and normally disposed to said front plate, a coin chute connected on each side of said bracket, one of said chutes receiving the twenty-five cent coins and the other chute for receiving the fifty cent coin pieces, means for partitioning each of the respective coin chutes into an acceptable coin channel and a return coin channel, said return coin channel of the respective coin chutes communicating with said coin return box, an electromagnet connected on said bracket, means associated with said electromagnet for preventing the passage of the coins from said coin slot to either of the coin accepting channels of the respective coin chutes when said electromagnet is deenergized, a coin rejector connected to said bracket below said coin separator for receiving the twenty-five cent piece and a coin rejector connected to the other side of said bracket for receiving the fifty cent pieces, each of said coin rejectors being operative to detect between acceptable and unacceptable coins of the respective coin denomination accepted thereby; each of said rejectors directing its acceptable coin piece to the acceptable coin channel of its respective coin chute, and directing its unacceptable coins to the unacceptable coin channel of its respective coin chute, and a trip switch associated with the acceptable coin channels of the respective coin chutes; each of said switches including a feeler disposed in the path of the coin passing through the acceptable coin channels, and the feeler disposed in the path of said fifty cent coin piece having a pair of lateral extensions adapted to be actuated twice by said fifty cent piece.

7. For use in a coin meter, a trip switch adapted to be actuated by an acceptable coin passing through said meter, said switch including a trip arm having a laterally bent end portion adapted to be contacted by said coin, said lateral end portion being provided with an offset portion intermediate the length thereof for engaging the edges of a coin adapted to actuate the same whereby hangup of the coin thereon is minimized.

8. The invention as defined in claim 7 wherein said offset portion is defined as a V-shaped notch, and said notch being dimensioned so that the side edges of the coin are received in the V of said notch:
